ELECTRIC-ARC LAMP.

1,026,568.

Specification of Letters Patent.

Patented May 14, 1912.

Application filed June 30, 1908. Serial No. 441,263.

To all whom it may concern:

- Be it known that I, KARL VON DREGER, electrician, residing at Belle-Alliancestrasse No. 92, in Berlin, Germany, a subject of the 5 Emperor of Austria-Hungary, have invented certain new and useful Improvements in Electric-Arc Lamps, of which the following is a full, clear, and exact description.
- The present invention relates to electric 10 arc lamps and has for its object the disposition of the carbons or electrodes therein in such fashion that the light from the arcs shall be enabled to pass unobstructedly downward in practically all directions.
- Another object of the present invention is 15 to provide means for steadyng the flame of the arc to substantially obviate flickering. To this end, the carbons are preferably arranged one above the other and a prefer- 20 ably substantially flat plate for steadyng the flaming arc is disposed above the upper carbon and out of contact therewith. The upper carbon is preferably the positive one; and it is caused to project somewhat beyond 25 the negative carbon, which may be effected initially when supplying the lamp with fresh carbons; but it is obvious, of course, that other means may be employed to this end.
- The ratio between the cross-sections of the 30 respective carbons is preferably such that the carbons will burn equally per unit of time; which ratio will vary according to the kind or kinds of carbon used, and should be determined by experiment. Owing to the fact 35 that the positive carbon burning tip normally projects beyond the burning tip of the negative carbon, the crater of the latter is able to emit the light produced in it, and indeed, that from practically the entire 40 length of the arc, freely and unobstructedly downward. Ordinarily the carbons are so arranged that they are located in the same vertical plane, one above the other, and both 45 are preferably disposed substantially horizontal.

The contacting of the carbons, which is necessary for striking the arc, may be produced by causing the point of one of said 50 carbons to move toward the point of the other when the lamp is switched on, but I do not desire to be limited to any particular means for striking the arc.

In the accompanying drawings I have ex-

emplified a preferred embodiment of my in- 55 vention, but it will be understood that the construction therein shown is merely by way of exemplification and that the invention is to be limited only by the scope of the claim appended hereto, since I am aware that 60 many changes and modifications may be made herein without departing from the spirit of my invention.

In said drawings like reference characters 65 designate like parts throughout the respective views.

Figure 1 is a somewhat diagrammatic section of an arc-lamp provided with two sets of carbons. Fig. 2 illustrates, in section, a modification of said lamp, means being 70 shown for spacing the carbons apart. Fig. 3 is a detail view of the carbon separating device.

Referring first to Fig. 1, a supporting, and preferably also shielding, plate Q car- 75 ries insulating brackets *e* from which project laterally the respective carbon-holders *c* and *d*. The holder *c* carries the upper or positive carbon *a*, while the holder designated *d* similarly carries the negative carbon *b*. 80 The inner extremities of a second pair of carbons *a'* and *b'* have been shown opposite those designated *a* and *b* and the lines joining the respective burning tips of the pairs of carbons will be angularly disposed with 85 respect to each other; or, in other words, the flame between the carbon *a* and *b* tends to throw its light downwardly and toward the left in Fig. 1, although some of the light will of course travel to the right, while the 90 flame between the carbons *a'* and *b'* will direct its rays downwardly and principally to the right. When the lamp is burning, each arc will normally remain at the inner ends of its respective set of carbons, being held there, 95 and not permitted to run in between the carbons, by electro-magnetic action. In Fig: 1 the positive and negative carbons are, when desired, rigidly clamped in their 100 holders which are suitably insulated one from the other by the insulating bracket or member *e*. The plate *Q* above the carbons not only serves as a support for the carbon holders, but further serves as a means for steadyng the flaming arc, or arcs, and this 105 plate should preferably be spaced out of contact with the upper carbon.

For striking the arc one or both of the car-

bons may be displaceably arranged in such a manner that when the lamp is switched in, their free ends may contact, the arc being struck when the ends of the carbons subsequently separate. In Fig. 2 one means for so striking the arc has been shown; a helical actuating rod *l* extending therebetween, said rod being mounted upon two pins *m* and *n*, which pins are rotatable in fixed bearings *o* and *p* which project downwardly from the supporting plate. A small handle may be provided at the outer extremity of the pin *m* so that the helical body of the rod may be rotated, which action will cause portions of the same to successively contact with different points along the carbons *a* and *b*. Thus as the pin *m* is rotated clockwise, as viewed in Fig. 3, the helical body of the rod *l* will engage the carbons *a* and *b* successively nearer to their holders, while vice versa when this body is rotated counter-clockwise the body *l* will, in effect, travel outwardly between the carbons, spacing them apart. This helical rod may hence be used to space the carbons apart, regardless of the length of the latter and the lamp may therefore be

switched on when the carbons are partly consumed.

What I particularly desire to emphasize is the importance of providing a shielding plate above the carbons for steadyng the flaming arc. If desired, a globe *h* of glass or the like may also be used to inclose the under side of the arc, but in many instances this will not be necessary.

Having now particularly described and ascertained the nature of my said invention and in what manner the same is to be performed, I declare that what I claim is:

A flaming arc lamp comprising a pair of carbons arranged substantially horizontal, one above the other, the burning tip of the upper of said carbons normally projecting beyond that of the lower carbon, and a plate for steadyng the flaming arc, said plate being disposed above the upper carbon and out of contact therewith.

KARL VON DREGER.
